UNITED STATES PATENT OFFICE.

HENDERSON PIERCE CHILDRESS, OF MEMPHIS, TENNESSEE, ASSIGNOR TO THE CHILDRESS MANUFACTURING COMPANY, OF MEMPHIS, TENNESSEE, A CORPORATION OF TENNESSEE.

COVER.

SPECIFICATION forming part of Letters Patent No. 746,675, dated December 15, 1903.

Application filed July 11, 1902. Serial No. 115,195. (No model.)

To all whom it may concern:

Be it known that I, HENDERSON PIERCE CHILDRESS, a citizen of the United States, residing at Memphis, in the county of Shelby 5 and State of Tennessee, have invented a new and useful Cover, of which the following is a specification.

This invention relates to covers for type-writing, adding, or other machines, and more 10 particularly to covers of that class described and protected by Letters Patent of the United States granted to me on July 8, 1902, and numbered 704,237.

One of the primary objects of the invention 15 is to improve this class of covers first by providing means which will automatically move them to inoperative position when released, said means also serving to keep the flexible covers employed in a smooth and 20 unwrinkled condition.

Another object is to improve the collapsible frames so that they will fold more compactly, and thus be out of the way.

Still other features reside in different 25 details of construction, which, together with their advantages, are fully described in the following specification and pointed out in the appended claims.

The preferred embodiment of the invention 30 is illustrated in the accompanying drawings; but it will be apparent upon an inspection of the claims that the structure herein set forth is open to various changes and modifications.

In said drawings, Figure 1 is a perspective 35 view of the cover when closed. Fig. 2 is a perspective view with the flexible covering removed. Fig. 3 is a vertical transverse sectional view through the structure. Fig. 4 is a vertical longitudinal section showing the 40 frame collapsed. Fig. 5 is a side elevation of a portion of the collapsed frame. Fig. 6 is a detail horizontal sectional view.

Similar numerals of reference designate corresponding parts in all the figures of the drawings.

The structure, as a whole, is very similar 45 to that set forth in the prior patent above mentioned, a base or platform 10 being employed, which may be constructed of any suit-

able material or in any desirable shape to 50 form a proper support for the casing. The present structure is especially designed for type-writers, and sockets 11 are arranged in the upper face of the platform to receive the feet of such type-writers. It is furthermore 55 provided with a peripheral ledge 12.

A casing is employed for covering the platform and the machine supported thereon, and for this purpose a foldable frame is provided, comprising a main bow 13, the ends of which 60 are pivotally connected by means of bolts 14 to the opposite edges of the base. Supplemental bows 15 are pivoted to this main bow and to each other in such a manner that they may be folded at the rear of the platform or 65 spread out, as shown in Fig. 2. To these several bows is secured a flexible covering 16, which may be of any suitable material that will exclude dust and moisture. It may be fastened to the bows in any manner desired. 70 A part of this flexible covering is secured to the base or platform, and to this end a portion of its edge is fastened to a holding-bow 18, that surrounds the rear edge of the platform behind the pivots, said bow fitting snugly 75 upon the ledge 12 and being secured in place by fastening-screws 19, one of which is indicated in Fig. 6. One of the supplemental bows 15 is hinged directly to the pivots 14 and is secured to the remaining edge of the 80 cover. This bow is of a size sufficient to fit about the remainder of the base in front of the pivots 14, and when the cover is in closed position it rests upon the forward portion of the ledge 12, as will be seen in Fig. 2. It is 85 held in this position by a lock, (designated as a whole by the reference-numeral 20,) which lock engages a suitable lip 21, secured to the bow.

In order that the cover when in closed position may constitute a rigid structure, the main bow 13 is braced by locking-arms 22, pivoted to the side edges of the platform and having detachable engagements with pins 23, secured to the said bow 13 and projecting 90 through the covering. They are held in inoperative positions by pins 24, arranged upon the side edges of the platform, said pins en-

gaging in openings formed in the arms. The cover is provided with a suitable handle 25, which may be of any desired construction and is located upon the top, being pivotally secured, through the medium of bolts 26, to the cross-arm of the main bow 13, which cross-arm is preferably strengthened by means of a bar, as 27.

The structure has been thus far described along the same lines as that set forth in the prior patent, and, indeed, the same reference-numerals have been employed in order that the elements may be more clearly compared. The changes and additions will now be described.

15 In the first place the frame of the original structure would not fold as compactly as desired, especially when used in connection with certain kinds of machines. This difficulty has been overcome by forming the side arms 20 of the lower bow of pivotally-associated sections 15^a, the side sections being journaled upon the pivots 14 and having sockets 15^b, in which the ends of the bow-sections are pivoted. As a result when the frame is 25 thrown backwardly to collapsed position the lower bow, which then comes uppermost, will fold down upon the next adjacent bow, as clearly shown in Fig. 4. Moreover, the relative swinging movements of the sections are 30 limited because of the pivoting of the ends of the bow-section between the ends of the socket, for when the bow-section is swung toward the platform it will first aline with the said sections, and afterward all the sections 35 are moved together, so that the lower edge of the cover will promptly close upon the platform. The portions of the side ledges 12 in rear of the pivots have been made wider, as shown in Fig. 6, so that the holding-bow 18 40 is arranged some distance within the other bows. Therefore when the cover is collapsed there is sufficient room to permit the several bows folding without scraping or unduly wearing the flexible covering. The terminals 45 of the other bows are held at the outer ends of the pivots by the ends 18^a of the holding-bow, which are sprung outwardly and constitute yielding washers, as clearly illustrated in Fig. 6. The construction of the pivots 14 50 is also different from the original arrangements. Screw-bolts are now employed, the nuts 14^a of which are embedded in the platform, the pivots having their inner ends threaded and engaging said nuts.

55 The lock 20 in the present instance is in the form of a latch-bolt 20^a, housed in a socket 20^b, formed in the front portion of the platform. This latch-bolt has an outwardly-projecting beak 20^c, which engages the lip 21 of the bow 15, as already described. It is normally held in its projected position by a spring 20^d, also fitted within the socket and bearing against the bolt. A suitable actuating-stem 20^e is secured to the bolt and projects beyond 60 the end of the platform and the casing, thus being in a convenient position to be operated. There is now employed means for automatic-

ally collapsing the casing or cover when it is unlocked, this means being preferably, though not necessarily, in the form of a coiled spring 70 28, one end of which is detachably engaged in an eye 29, formed upon the rearmost supplemental bow 15, the other end being detachably secured behind the holding-bow 18, so that the spring may be removed when desired and replaced by a new one should it become broken or worn. In order to relieve the platform 10 of the strain and weight of the type-writer or other machine placed thereon, a brace-bar 30 extends across the under face 80 of said platform, and its terminals are upturned, as shown at 31, to form ears, through which the pivots 14 are passed. It will be apparent that this feature greatly strengthens the entire structure. 85

The machine to be protected is placed upon the platform in the usual way, so that it will not interfere with the free movement of the cover, and said cover may be swung over the same and locked, thus completely protecting 90 the inclosed machine from dust and dirt. If the machine is to be carried about, the braces 22 are moved to their operative position, and thus the main bow is positively locked against movement with respect to the platform, and 95 the flexible cover is consequently relieved of any strain. If the machine is not to be transported, it is not necessary to employ these braces, as the covering will hold the frame in proper position. To open the cover, it is only 100 necessary to press upon the thumb-piece 20^e, thereby unlocking the lower bow 15 and permitting the spring 28 to act. This spring drawing downwardly upon the rear portion of the frame will cause the same to move slowly 105 backward and collapse to the position shown in Fig. 4. It will be apparent that these several additions and changes in the structure constitute important improvements over the original disclosures, as shown by the various 110 advantages above pointed out.

From the foregoing it is thought that the construction, operation, and many advantages of the herein-described invention will be apparent to those skilled in the art without further description, and it will be understood that various changes in the size, shape, proportion, and minor details of construction may be resorted to without departing from the spirit or sacrificing any of the advantages 115 of the invention. 120

Having thus described my invention, what I claim as new, and desire to secure by Letters Patent, is—

1. In a cover of the class described, a support for a type-writer or like machine, a collapsible casing mounted thereover, means for holding the casing in extended position, and means for automatically collapsing the casing when the holding means is released. 125

2. In a cover of the class described, a support for a type-writer or like machine, a collapsible casing mounted thereover, a lock for holding the casing in extended position, and 130

- a spring engaging the casing to automatically collapse the same when released.
3. In a cover of the class described, the combination with a suitable support for a type-writer or like machine, of a collapsible casing mounted upon the support, means for holding the casing extended over the support, and means for automatically collapsing the casing when released from the holding means.
- 10 4. In a cover of the class described, the combination with a suitable support for a type-writer or like machine, of a collapsible casing mounted upon the support, a locking device movably mounted upon the support and detachably engaging the casing to hold it extended over the support, and means for automatically collapsing the casing when it is released from the lock.
- 15 5. In a cover of the class described, the combination with a suitable support for a type-writer or like machine, of a collapsible casing mounted upon the support, and a spring engaging the casing to collapse the same when released.
- 20 6. In a cover of the class described, the combination with a suitable support for a type-writer or like machine, of a collapsible casing mounted upon the support, and a yielding connection between the support and the casing, said connection being arranged to automatically move the casing to its collapsed position.
- 25 7. In a cover of the class described, the combination with a suitable support for a type-writer or like machine, of a collapsible frame pivoted to the support, a flexible covering attached to and movable with the frame, and
- a spring connected at one end to the support, and at the other end to the frame.
8. In a cover of the class described, the combination with a supporting platform for a type-writer or like machine, of a collapsible frame pivotally mounted upon the platform, a flexible covering secured to the frame, and a coiled spring detachably secured at one end to the frame and at the other end to the platform.
- 40 9. In a cover of the class described, a collapsible casing for type-writers and like machines comprising a folding frame made up of swinging bows, and a flexible covering secured to the bows, one of said bows comprising pivoted side sections having sockets in their free ends, and a bow-section having its ends pivoted in intermediate portions of the sockets, the swinging movement of said bow-sections upon the side sections being limited by the walls of the sockets.
- 45 10. In a cover of the class described, the combination with a support, of a collapsible casing mounted thereon and movable over the support, a spring for automatically collapsing the casing, and a spring-pressed latch mounted on the support and arranged to engage the casing and hold the same over the support, said latch having an exposed actuating device.
- 50 11. In testimony that I claim the foregoing as my own I have hereto affixed my signature in the presence of two witnesses.
